UNITED STATES PATENT OFFICE.

DONALD R. WILLS, OF WASHINGTON COURT HOUSE, OHIO.

CHARGE-FORMING DEVICE.

1,408,671.

Specification of Letters Patent. Patented Mar. 7, 1922.

Application filed April 29, 1919. Serial No. 293,470.

To all whom it may concern:

Be it known that I, DONALD R. WILLS, a citizen of the United States, residing at Washington Court House, in the county of

5 Fayette and State of Ohio, have invented certain new and useful Improvements in Charge-Forming Devices, of which the following is a specification.

This invention relates to those charge-forming devices for internal combustion engines, having means designed to automatically effect proportional intake of fuel and air, and embodies improvements on my Patent 1,263,501, dated April 23, 1918.

15 My present improvements relate, first, to such novel location of the throttle valve, in relation to the chamber in which the air and fuel are mixed, that new and improved results are obtained as will be hereinafter set

20 forth.

My invention relates, further, to means whereby the mixture or charge may be pre-heated before delivery to the engine either before the engine is started, or to utilize the 25 exhaust gases for preheating the charge or mixture when the engine is running, as particularly pointed out hereinafter.

The present invention contemplates, third, a novel relationship and combination of an 30 air metering device, metering device for the fuel valve, and a spring, the spring being so related to the air and fuel metering devices that it is adapted to perform several different functions, such as will be pointed 35 out in detail hereinafter.

A fourth feature of my present invention 40 comprises an air metering device, a fuel intake controlling needle valve and setting mechanism therefor combined as a unitary or self-contained device adapted for application to, or removable from, the carburetor shell or casing as such.

In its fifth aspect, the invention embodies 45 and air metering inlet member or part which has a tapering interior and is so secured and related to the other parts that it can be removed and another air metering inlet part substituted having a different angled interior wall, whereby by using different ones 50 of said air metering inlet members with the same metering device, a greater or lesser volume of air may be admitted with a given movement of the metering device and, consequently, the charge forming device or carburetor is thereby made adaptable for use 55 in connection with any engine.

My invention has for its sixth object the provision of improvements comprising air metering means, fuel metering means, a spring related thereto in a novel manner, 60 and setting and controlling means cooperatively combined so that torsion on the spring may be changed and the air metering device and fuel intake controlling means may be set and controlled to meet any requirements of choking, starting, and operating the engine that may have to be met. The invention provides, in that respect, a combined carburetor and choker which, so far as I am aware, I am the first to provide. 65 70

The invention is set forth in detail hereinafter and the individual and joint functions of the parts explained as pertaining to the best embodiment of the principles of the invention of which I have knowledge at 75 the present time, but the disclosure is to be considered as illustrative rather than restrictive of the scope of the invention as I am aware that modification may be resorted to. 80

In the accompanying drawings:

Figure 1 is a vertical section, certain parts being in full lines;

Figure 2, an elevation taken at right angles to Figure 1, certain of the parts 85 being in section;

Figure 3, a plan view;

Figure 4, a detail of the regulator;

Figure 5, a detail of the rocker with which the regulator cooperates; and 90

Figure 6, a section on the line 6—6 of Figure 5.

The shell or casing is shown at 1 and the fuel reservoir at 2. The fuel reservoir 2 is supported from the shell or casing 1 by a 95 combined air and fuel conduit member 3 which has a flange 4 on which the reservoir 2 rests and is connected by screw threads 5 to the bottom 6 of the shell or casing which serves as a top for the fuel reservoir. It is 100 possible, however, to turn the reservoir 2 around to different positions as it is not fastened to the part 3. When assembled for use, however, the member 3 is screwed up so that the upper edge of the reservoir 2 is 105 clamped firmly against the top member 6. The fuel from the reservoir 2 passes through the ports 7 into the primary mixture chamber or venturi 9. The air enters the hollow interior of the member 3, as at 10, and passes 110 upwardly into the primary mixture chamber 9 around the mouth 11 where the fuel

enters said chamber, as shown by the constricted portion 12. A needle valve 13 controls the open mouth 11, said valve being set and operated as hereinafter described.

5 A float 14 in the fuel reservoir 2 is suitably pivoted at 15 and controls a fuel admission valve 16.

The flange or coupling for the pipe or manifold leading to the engine appears at 10 17. The secondary mixture chamber of the casing 1 is shown at 18.

15 A throttle valve 19 controls the passage of the charge or mixture from the chambers 9 and 18 to the chamber 20 from which the charge or mixture passes to the engine. The throttle valve 19 is so placed that it constitutes, in effect, a side of the chamber 18 and is located immediately adjacent the mouth of the primary mixture chamber 9. By locating the throttle valve 19 close to the chamber 9 and, in effect, causing said throttle valve to constitute one side of the chamber 18, very great advantages are obtained over results had when the throttle valve is located 20 at a point spaced from the mouth of the chamber 9 and from the side of the chamber 18 as will be hereinafter pointed out.

Extending vertically within the chamber 30 20 are tubes or conduits 21 whose upper ends may discharge into a box 22 having an outlet 23. The lower ends of the tubes or conduits 21 communicate with a chamber 24 to which is suitably connected a nipple 25 which may be connected in any suitable manner as, for 35 instance, a flexible metal pipe, to the exhaust manifold of the engine or to any other part of the exhaust system so that the exhaust gases derived from the engine will be conducted to the chamber 24, thence to pass upwardly through the tubes or conduits, thus heating the chamber 20 and the charge in 40 said chamber when en route to the engine, the advantages of which will appear hereinafter.

45 To provide for the admission of heat within the tubes or conduits 21 when the engine is not running, so that the mixture may be heated when the engine is to be started, there is provided a branch 26 for the nipple 25, said branch being provided with a removable cap 27 to which is connected a rod 28 carrying on its end a wad of absorbent asbestos or similar material 29 which may be soaked in a fuel such as gasoline, for instance, prior to 50 introduction into the nipple 25. A hole 30 in the branch 26 may be made to register with a corresponding hole in the cap 27 for the admission of air to the interior of the branch 26. After the engine has been 55 started the cap 27 may be turned to close the opening 30, the tubes or conduits 21 then obtaining their heat from the exhaust. When the engine is to be started, the wad or ball 29 can be provided with gasoline or a fuel, ignited, and the cap placed in position with

the port 30 open. Air will then enter to support combustion and the heat rising through the tubes 21 will warm the charge or mixture so that the engine may be readily started.

60 A flanged shell 31 fits snugly within the mouth 32 of the shell or casing 1 and is provided with arms 33 which have a bearing 34 for the stem 35 which carries the needle valve 13, said bearing permitting the stem 35 to both slide and turn. Removably seated 65 inside the shell 31 is a flanged air metering part or head 36 which has a downwardly flared conical interior wall 37. Screws 38 70 secure the head 36 and shell 31 to the mouth 32. On removing these screws the metering head 36 can be taken out and another substituted therefor having an interior wall 37 of greater or lesser angle than the one previously used. Consequently, provision is 75 made whereby my invention is adaptable for use in connection with any internal combustion engine, as, according to the angle of the wall 37, a greater or lesser measured volume 80 of air will be admitted when the device is in operation.

85 A yoke 39, which is secured by the screws 38, serves as a bearing to permit sliding and turning of the upper portion of the needle valve stem 35, said yoke having a fixed arm 40. Pivoted at 41 to the outer end of the 90 arm 40 is a hollow regulating scale 42, Figs. 2 and 5, which has a slot 43 in its lower end.

95 Secured to or carried by the head 36 is a tubular shell 44 to which is secured a dial 45, Fig. 1. The controller or regulator shown 100 in Fig. 4 operates in the shell 44, said controller being provided with a ball end coupling 46 which is received in the lower end of the scale 42 and has a pin 47 which turns in a slot 48 in the shell. A knurled head 49 105 carries a pointer 50 which indicates on the dial 45 the position of the needle valve 13 as will appear hereinafter.

110 The stem 35 has a slot 51. Slidably mounted on the stem 35 is the air metering disk 52 whose margin, in connection with the wall 37, determines, according to the 115 position of said disk, the volume of air measured or metered into the device. The disk 52 is formed integral with or connected to a sleeve 53 which is provided with a key 54 extending through the slot 51. Consequently, the disk 52 can move up and down 120 on the stem 35 and will yet always turn with the stem and will not interfere with the turning of the stem, nor will the turning of the stem interfere with the position of the disk. Secured to the stem 35 is a collar 55. A coil spring 56 surrounds the stem 35 and the lower portion of the sleeve 53 and bears 125 against the collar and the disk 52 with sufficient force to not only press the disk 52 upwardly and the stem 35 downwardly but, also, to rotate the stem 35 and with it the needle valve 13 for the purpose of holding 130

an arm 57 carried by sleeve 53, against the scale 42 as shown in Figs. 1, 2 and 3, except under certain conditions brought about by setting the parts.

5 Carried by the upper end of the stem 35 is a cam 58. Mounted to turn on the stem 35, just below the cam 58, is a controlling cam 59 which has an operating cross piece or handle 60 provided with means 61 by 10 which it may be connected to means suitably positioned for the driver of the car to operate it. To prevent the cam 59 from rising, there is provided a yoke 62 secured to the arm 40, as shown in Fig. 1, said arm having 15 its parts lying in a groove in the cam 59.

It will be observed that the provision of the arm 57 enables cooperation to be had between the scale 42 and the stem 35 regardless of the movement of the disk 52.

20 The knurled head 49 may be provided with a crank or other means 63 for attachment of any operative connection leading to a point convenient for control by the driver of the automobile. The throttle valve 19 has a 25 crank 64 to which any suitable operative connection may be attached leading to the foot pedal or throttle control device of the car.

If gasoline is the fuel used, the air and 30 gasoline are in the form of fine globules in the venturi or primary mixture chamber 9 and in more finely divided form in the secondary mixture chamber 18. The throttle valve 19 being located so close to the upper 35 mouth of the chamber 9, when the engine is at low speed, such as will be the case immediately after starting, all globules of gasoline are readily broken up and carried past the throttle valve instead of lodging 40 on the sides of the casing to later overload the engine. Consequently, the location of the throttle valve in relation to the mouth of the chamber 9 and as constituting the side of the chamber 18, has the great practical 45 advantage of preventing gasoline in liquid form from passing the throttle. The location of the throttle 19 close to the venturi 9 insures a quick "pick up" as this position causes the air stream to be converged over 50 the top of the venturi. Heretofore, so far as I am aware, the throttle valve has been located relatively distant from the point of mixture, and hence there is a passage or 55 space on the walls of which the liquid gasoline accumulates, ready to rush into the engine and overload it if the throttle is opened quickly. With a throttle valve located according to my invention, there is no possibility of such action.

60 The charge which has been formed in the chamber 20 strikes the heated tubes or conduits 21 and is preheated before passing to the engine, with the usual advantages both in starting and during operation of the engine.

The present day carburetors operate on the principle of using sufficient vacuum to pull the gasoline mixture into the motor. The vacuum is raised too high in the manifold and in order to obtain a vacuum, small openings are used, but small openings do not admit sufficient gasoline and air to obtain the highest efficiency from the motor. The metering disk 52 of my invention is not for the purpose of closing the opening in the head 36, but for the proper proportional admission of air to later mix with gasoline according to the vacuum or suction. In the use of my charge-forming device, it is not necessary to impose upon the motor or 70 engine the duty of producing such a vacuum as the usual present day carburetor demands of the engines with which it is used; consequently, the efficiency of an engine with which my charge-forming device is used is 75 greatly increased. Furthermore, there is no place where the fuel and air are not metered 80 correctly.

Heretofore it has been a common practice to have a separate choking device 90 whereby a very rich mixture, with a little air, is introduced into the engine when the latter is started. In my invention the choking action is carried out by the device itself. By turning the lever or arm 60 so that the 95 cam 59 will raise the cam 58 and hence pull up the stem 35, thereby further opening the needle valve 13 and also placing an increased or greater tension on the spring 56, not only is the supply of fuel, such as 100 gasoline, proportionally increased so that the mixture is very rich, but the metering disk 56 being thus placed under greater spring pressure, will not meter in as much air as previously, causing an excess vacuum 105 which, in turn, quickly increases the inflow of gasoline. Consequently, when the engine is to be started, by turning the member 60 a choking action is obtained and when the engine has been started, the cam 110 59 can be turned back so that normal operation will follow. Furthermore, while a choking action may be obtained with the present device, flooding of the engine with gasoline and causing it to stop, is prevented 115 because, while choking is obtained, it is impossible to completely close, or hold closed, the metering disk 52, and even with the increased spring tension, the metering disk will let in sufficient air so that the motor 120 will not stop. Over choking of the motor and its injury from such action, are prevented in the use of my invention.

The spring 56 performs several functions, namely: It presses the metering disk upwardly and the stem 35 downwardly to move the needle valve 13 toward its seat 11; the said spring has a torsional action so that the arm 57 is kept in contact with the scale 42 regardless of the position to which 130

said scale 42 may be adjusted; when the arm 60 is turned to the left, Fig. 2, the rise of the cam section 58 pulls up the stem 35 and increases the tension of the spring 56 and, consequently, the metering disk 52 is held in position by a heavier spring pressure, thus enabling choking to be carried on but without possibility of stopping the motor, for while the disk 52 offers greater resistance to admission of air around its margin, nevertheless, it cannot be completely closed. The torsional action of the spring 56 keeps the arm 57 against the scale 42 no matter what adjustment of the regulator of Fig. 4 may be effected after the arm 60 has been moved to place a greater tension on spring 56, as previously described, when choking is being carried on, or subsequently. After the motor has been choked for starting the engine, the regulation effected by turning the finger piece 49 consists in the turning of the arm 57 and with it the metering disk 52 and the stem 35 so that the cam section 58, by riding on the cam section 59, effects the proper adjustment of the fuel supply past the needle valve 9 for it will be seen that the turning of the stem 35 by the scale 42 results in either lifting or lowering the said stem 35, and, with it, the needle valve 13.

The metering disk 52 may be made sufficiently heavy so that by reason of its turning with the stem 35 it will have no tendency to flutter when the engine is under a heavy load.

What I claim is:

1. In a charge-forming device, the combination with a valve for controlling the admission of fuel, of an air metering device mounted for movement in relation to the valve and also for turning bodily therewith, a cam carried by the valve, and a controlling cam adapted to be set and with which the first named cam engages, said cams being adapted for adjusting the valve in relation to the air metering device, whereby the desired proportional admixture of air and fuel may be regulated at will.

2. In a charge-forming device, the combination with a valve for controlling the admission of fuel, of an air metering device mounted for movement in relation to the valve and also for turning bodily therewith, a cam carried by the valve, and a controlling cam adapted to be set and with which the first named cam engages, said cams being adapted for adjusting the valve in relation to the air metering device, whereby the desired proportional admixture of air and fuel may be regulated at will, and supplemental regulating means for turning the valve to effect additional adjustment thereof by the coaction of said cams.

3. In a charge-forming device, the combination with a valve for controlling the

admission of fuel, of an air metering device mounted for movement in relation to the valve and also for turning bodily therewith, a coil spring cooperating with the air metering device and with the valve, and cooperating cams for adjusting the valve in relation to the air metering device and at the same time increasing the tension of the spring, whereby the desired proportional admixture of air and fuel may be regulated at will. 75

4. In a charge-forming device, the combination with a valve for controlling the admission of fuel, of an air metering device mounted for movement in relation to the valve and also for turning bodily therewith, a coil spring disposed between the air metering device and the valve and cooperating with both of them, said spring being adapted to move the valve towards its seat and to hold the air metering device in normal position, 85 said spring also serving to turn the valve, and means for adjusting the valve in relation to the air metering device to thereby change the volume of fuel admitted, and increase the spring tension on the air metering device.

5. In a charge-forming device, the combination with a valve for controlling the admission of fuel, of an air metering device mounted for movement in relation to the valve and also for turning bodily therewith, a coil spring disposed between the air metering device and the valve and cooperating with both of them, said spring being adapted to move the valve towards its seat and to hold the air metering device in normal position, said spring also serving to turn the valve, means for adjusting the valve in relation to the air metering device to thereby change the volume of fuel admitted, and increase the spring tension on the air metering device, and a supplemental regulator adapted for turning the valve and the air metering device to cause further action of the means last mentioned to further regulate the position of the valve. 100

6. In a charge-forming device, the combination with a needle valve controlling the admission of the fuel, said valve having a stem provided with a cam section, of a metering disk having a loosely splined and slideable connection with the valve stem, a coil spring surrounding the stem and engaged with it and also cooperating with the metering disk, said spring being adapted to resist metering movement of the metering disk, and to force the needle valve towards its seat and cause axial turning of the needle valve stem due to the action of the cam section aforesaid, a cam section with which the aforesaid cam section engages, whereby the stem and valve may be adjusted to regulate the fuel supply and by means of which, in conjunction with the action of the spring, the needle valve, its stem, and the air meter- 130

ing device will be caused to turn, a scale, a supplemental regulator for shifting the scale, and an arm carried by the stem which cooperates with the scale, whereby the stem 5 and needle valve may be further adjusted.

7. In a charge-forming device, the combination with air metering means, of fuel metering means, said air metering means and fuel metering means being movable to 10 ward and away from each other and connected for turning bodily together, a spring cooperating with both of said means and adapted for moving them in opposite directions, and means for adjusting the air meter- 15 ing intake means and fuel metering means at will independently of each other while also varying the tension of said spring.

8. In a charge-forming device, the combination with a valve for controlling the admission of fuel, of an air metering device 20 mounted for movement in relation to the valve, a primary mixture chamber or venturi, a secondary mixture chamber located between the venturi and the air intake, and a throttle valve disposed immediately adjacent the mouth of the venturi and also constituting a part of the wall of the secondary mixture chamber, said throttle valve causing the air stream to be converged over the top 25 of the venturi and preventing gasoline in 30 liquid form from passing to the engine.

In testimony whereof I affix my signature.

DONALD R. WILLS.
